UNITED STATES PATENT OFFICE.

SILAS A. ILSLEY, OF BROOKLYN, NEW YORK.

DESIGN FOR CANISTERS FOR TEAS, COFFEES, &c.

Specification forming part of Design No. 7,070, dated December 23, 1873; application filed November 18, 1873.
[Term of Patent 7 years.]

B.

To all whom it may concern:

Be it known that I, SILAS A. ILSLEY, of Brooklyn, in the county of Kings and State of New York, have made or produced a Design for a Sheet-Metal Canister for Teas, Coffees, Spices, or other articles, of which the following is a description:

In the drawing, Figure 1 is a sectional plan, and Fig. 2 is a perspective view, of said canister.

The general configuration of said canister is cubical, with bottom, sides *a*, back *d*, and flat portion *e* of top. The lid *f* and canister at the sides *g* thereof are concave, and in the form of a segment of a cylinder. The front of the canister has before been made of a compound curved plate, usually known as an ogee. I make this front as a segment of a cylinder, *h*, and at each side thereof are flat portions *k*, that stand at an inclination or bevel,

so that the vertical angles of the canister extend out as far, or nearly so, as the curved front. This form I call a pegee-bevel front canister.

I do not claim a canister with a front of an ogee shape, nor one composed of segments of one large and two small cylinders; neither do I herein claim a canister-front with a cylindrical segment and two side portions in the same plane, this being the subject of a separate application.

I claim—

The design of the shape and configuration of the canister, with the beveled and segmental ornamental front specified.

Signed by me this 17th day of November, 1873.

Witnesses: S. A. ILSLEY.
